REPLENISHING MECHANISM FOR LOOMS

Harrison N. Thibault and Roland L. Plante, Hopedale, Mass., assignors to Draper Corporation, Hopedale, Mass., a corporation of Maine

Filed Sept. 15, 1958, Ser. No. 761,127

11 Claims. (Cl. 139—247)

This invention relates to looms for weaving and, in particular, to improvements in the timer mechanism for air-operated filling bunch control means for use with automatic batteries for looms wherein a supply of bobbins or filling packages is automatically controlled incidental to transfer to a shuttle.

It is a general object of this invention to provide a timer mechanism effective to control the operation of both an extractor mechanism for removing the filling bunch from a bobbin and a suction device for holding and withdrawing said filling bunch from its bobbin.

It is a further object to provide a timer mechanism which is responsive to the transfer device of the loom thus causing an actuation of the extractor mechanism for a short period of time while simultaneously permitting passage of air to a suction device for a longer period of time.

It is a further object to provide a timer-valve means having valved compartments wherein the valves are simultaneously opened by the transfer device of the loom but which are caused to be closed independently so that the periods of time during which air may be supplied from two of the compartments may be varied with respect to each other.

It is a further object to provide a timer mechanism having as a part thereof a valved compartment which may be controlled in conjunction with the loom control means so that the air supply is shut off at any time when the loom is not running.

Other objects will appear from the following detailed description of the device.

In United States Patent No. 2,845,957 there is disclosed a suction thread disposal means as a part of a filling bunch extractor connected to an air system at the loom and controlled by a timer means acting to valve air to the system upon the initial movement of the members of the bobbin transfer system. The timer disclosed therein operates to actuate an air-controlled extractor head which operates to remove the tip bunch from its bobbin and simultaneously provides suction to a device which holds and finally removes this bunch as well as the filling end of the exhausted, outgoing supply from the selvage to the usual Stafford type cutter mechanism at the proper instant. Such a timer, however, after a period of time tends to become inaccurate in its operation due to its becoming clogged by lint at that point where air is permitted to bleed into the timer to close the valve to the suction device. Thus, the period of time during which the suction device is in operation is not constant.

According to the instant invention, a timer mechanism has been devised which is controllable to extremely accurate limits over indefinite periods of time. The valve controlling the air supply to the suction device is permitted to be closed by a positively driven mechanism and a spring clutch permits the valve to be closed only as it is actuated by this mechanism. The positively driven mechanism in turn is actuated only by movement of the lay.

2

The invention will be described in greater detail by reference to the accompanying figures of drawing, in which:

Fig. 1 is a front view of a portion of a loom showing 5 the timer assembly attached thereto.

Fig. 2 is an end view of a portion of the right side of the loom.

Fig. 3 is a close-up of a portion of Fig. 1.

Fig. 4 shows an enlargement of a small portion of 10 Fig. 2 showing parts of the timer with the loom shut off.

Fig. 5 shows a view similar to that of Fig. 4 with the loom running.

Fig. 6 is a plan view of the timer assembly.

Fig. 7 is an end view as seen from the left of Fig. 6.

Fig. 8 is a view taken on line 8—8 of Fig. 7.

Fig. 9 is a view taken on line 9—9 of Fig. 8.

Fig. 10 is an end view with parts in section as seen from the right side of Fig. 8.

In Figs. 1 and 2 the timer mechanism is denoted by 20 the letter T and is mounted to the right side of the loom by means of an air valve bracket 11. An inlet plunger depressor arm 12 is pivotally mounted on the bracket at 13 and the inlet plunger depressor 14 is fixed so that it is movable with the depressor arm to the right as shown 25 in Fig. 5 when the loom is running and to the left as shown in Fig. 4 when the loom is shut off. Movement of the depressor arm in one direction or the other causes a corresponding movement of a plunger 15 for a purpose to be described later. Movement of the depressor arm 30 in one direction or the other is governed by the position of the shipper arm 16 so that when the loom is running the plunger 15 is depressed and when the loom is off the depressor arm and plunger are just touching each other.

As shown in Fig. 2 a pawl linkage bracket 17 is fixedly 35 mounted at its lower end to the sword 18 and has a slot formed in its upper end for receiving one end of a pawl linkage connecting rod 19. The latter at its other end is pivotally connected to one end of a pawl lever 20. Thus, as the sword 18 moves back and forth during operation of the loom, the pawl lever is caused to reciprocate.

A valve depressor 21 causes depression of the plunger 22 and is actuated by rearward movement of the bobbin transfer mechanism of the loom. Return of the plunger 22 back to its normal position is effected through reciprocation of the pawl lever in a manner to be described.

As seen in Fig. 8 the timer assembly comprises an air valve 35 interconnecting compartments 24 and 25. A valve head 26 is threadably mounted to a valve body 23 forming a portion of compartment 25 and containing 50 a third co-axial compartment 27. The air valve body contains a pressure chamber 28 and passageway 29 separated by a valve 30 mounted on one end of the plunger 15 and biased in the direction of the passageway 29 by means of a spring 31. An inlet union 32 interconnects an air inlet hose 33 with the chamber 28.

Compartment 24 and passageway 29 are interconnected by means of a further passageway 34 and compartment 24 is normally closed at one end by a valve 35 biased by a spring 36 and mounted intermediate a timer plunger 37, and at its other end is sealed by an air valve head 38 having an opening therein to permit the passage through the valve head of the plunger 37.

Thus, it may be seen that when the shipper arm is in the "off" position as seen in Figs. 2 and 4, the plunger 65 15 is in its outermost position and the valve 30 is thus closed and no air can be received in the air valve body beyond the chamber 28. When the shipper arm is pulled forward of the loom the inlet plunger depressor arm 12 is moved rearwardly moving with it the depressor 14 70 which causes a depression of the plunger 15, opening the valve 30 and permitting air under pressure to fill the

compartment 24. The valve 35 normally prevents escape of air beyond this compartment.

The valve head 26 has formed therein an outlet opening with which is threadedly engaged a tube fitting 39 for connecting a tube to a filling bunch extractor head (not shown) which may be similar to that shown in United States Patent No. 2,845,957. The plunger 22 is insertable through an opening in one end of the valve head 26 and has fixed to the inclosed end of the plunger a valve 40. The plunger 22 further contains two radial openings 41 and 42 interconnected by an axial passageway 43. The openings are located so that when the valve 40 is closed, the opening 41 appears outside of the valve head and opening 42 appears within the head. A spring 43 keeps the valve 40 closed and also prevents rotation of the plunger 22. An opening 44 in the compartment 25 permits interconnection of a tube with a suction device connected to the extractor for removal of the filling bunch after it has been cut by the usual Stafford type thread cutter. The left end of the timer plunger 37 as seen in Fig. 8 is in close proximity to the valved end of the plunger 22 so that as the transfer mechanism of the loom causes a depression of the plunger 22, the valve 35 will be caused to open as well as the valve 40. An inlet air plunger guide 45 is fixed to the outer circumference of the valve head 26 and has an opening therein for supporting the plunger 15. Rubber O-rings R are insertable into slots in the valve body or outlet connections to prevent the escape of air as shown in Fig. 8.

An escapement bracket 46 is fastened to an extension 47 of the valve body at 48 and 49. Approximately centrally of the bracket there is inserted a ratchet gear stud 50 as shown more clearly in Figs. 9 and 10. A ratchet gear 51 is mounted thereon on one side of the bracket 46 against a ratchet gear bearing 52. A stud washer 53, a clutch gear 54 and clutch spring 55 are mounted in that order on the other side of the bracket. A shoulder 56 formed in the stud at one end and a nut 57 threadedly engaged at its other end permit assembly of the unit. The spring clutch assembly just described permits free and independent rotation of the stud gear clockwise as seen in Fig. 8 but rotation of the stud in a counterclockwise direction binds upon the clutch spring thereby tending to rotate the ratchet wheel simultaneously with it. However, two separately actuatable pawls 58 and 59 prevent counterclockwise rotation of the ratchet except when the pawls are themselves independently actuated each by rocker arms 60 and 61 fixed upon the pawl lever stud 62.

A toothed rack 63 is received at one end in a groove in the plunger 37 and rests upon the stud gear 54. An escapement clutch cover 64 having a slot 65 formed therein is fastened to one side of the escapement bracket 46 and a bracket cover 66 is fastened to the other side of the bracket. The pawl lever 20 is fixed to the pawl lever stud so that reciprocation of the former actuates the pawls alternately through their respective rocker arms.

In the operation of the timer assembly, movement of the shipper arm forward causes a depression of the plunger 15 thus admitting air under pressure into compartment 24. When a call for transfer of a bobbin is made thereby affecting the transfer mechanism of the loom, the valve depressor 21 actuates the plunger 22 thus opening valve 40 which in turn actuates plunger 37 opening valve 35. Thus, air under pressure is admitted to compartments 25 and 27 and to the suction device and extractor head, respectively. Release of the transfer mechanism returns the valve depressor to its normal position and the spring 43 permits valve 40 to return to a closing position. The air under pressure in compartment 27 leaks out fairly rapidly through radial openings 42 and 43 and their interconnecting passageway so that the extractor head is returned to its usual position in a relatively short period of time.

However, it is desired to maintain air pressure to the suction device for a comparatively longer period of time

by providing air through the opening 44. Thus, as the plunger 37 is depressed, the rack 63 is caused to move to the right as seen in Fig. 8 rotating the clutch gear 54 clockwise in its freely and independently movable direction. The spring 36 tends to return valve 35 immediately to a closing position but is prevented from doing so by the pawl and ratchet assembly, since movement of the clutch gear in a counterclockwise direction requires simultaneous movement of the ratchet wheel in the same direction due to the action of the spring clutch. Reciprocation of the sword causes a reciprocation of the pawl lever through the connecting assembly shown in Fig. 2, which transfers such motion to the fixed rocker arms and subsequently to the pawls alternately, thus permitting a slow counterclockwise movement of the ratchet wheel, thus permitting the valve 35 to return to a closed position.

Obviously, the valve depressor 21 may be adjusted to increase or decrease the amount of depression of the plunger 22, thus resulting in a corresponding increase or decrease in the period of time in which air is admitted to the outlet 44.

While one embodiment of the invention has been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

We claim:

1. A timing means for timing the action of a tip bunch extractor in a loom for weaving, said timing means comprising a first spring-biased valve for admitting a continuous flow of air under pressure into a first compartment of said timing means when said loom is in operation, a second spring-biased valve in said first compartment adapted to control passage of air from said first compartment into a second compartment co-axial therewith, said second compartment having an opening in its side permitting flow of air under pressure to an ejector and including suction thereat, a third spring-biased valve in said second compartment co-axial with said second valve adapted to be actuated by the transfer mechanism of the loom whereby said second valve is caused to open, said third valve normally closing off a third compartment which has an opening in its side for admitting air under pressure to said extractor.

2. The mechanism of claim 1 wherein said second valve, upon being opened by the transfer mechanism, is held open by means of a spring clutch assembly and slowly released therefrom by means of a pawl and ratchet assembly actuated by movement of the lay, thus providing a supply of air under pressure to said ejector for an extended period of time.

3. The mechanism of claim 1 wherein said third valve is mounted on a plunger axially spaced from the plunger supporting said second valve, said third valve plunger having an axial passage therein terminating at two radial passages in said plunger, whereby air may be readily released from said third compartment permitting said third valve to assume a closing position prior to said second valve.

4. A timing means for timing the action of a tip bunch extractor in a loom for weaving, said timing means comprising a first valve permitting passage of air under pressure to a first compartment when said loom is in operation, a second valve in said first compartment to control air supply to a suction means, and a third valve in a second compartment co-axial with said first compartment to control air supply to said extractor, said second valve being permitted to be returned independently to a closing position by a positively driven means.

5. The timing means of claim 4 wherein said positively driven means comprises a pawl and ratchet wheel assembly adapted to be actuated by the lay of the loom.

6. The timing means of claim 4 wherein said third

valve is mounted on a plunger having an axial part therein through which air for said extractor may be exhausted, thus permitting a relatively rapid return of said third valve to a closing position.

7. A timing means for timing the action of a tip bunch extractor in a loom for weaving, said timing means comprising a series of three axially aligned communicating compartments, a valve in a first of said compartments for admitting air under pressure from said first to a second of said compartments adjacent thereto, a further valve in said second compartment for admitting said air from said second to a third of said compartments, said further valve being adapted to control opening of said first-mentioned valve, and time controlled means effective to maintain the latter in open position for a predetermined period of time.

8. Mechanism as defined in claim 7 wherein said first-mentioned valve is adapted to be actuated by means including the transfer setting members of the loom.

9. Mechanism as defined in claim 8 wherein said time controlled means is also actuated by said members.

10. A timing means for timing the action of a tip bunch extractor in a loom for weaving, said timing means comprising a series of three axially aligned communicat-

ing compartments, a valve in a first of said compartments for admitting air under pressure from said first to a second of said compartments adjacent thereto, a further valve in said second compartment for admitting said air from said second to a third of said compartments, said further valve being adapted to control opening of said first-mentioned valve, and time controlled means effective to maintain the latter in open position for a predetermined period of time, said time controlled means including a spring clutch means having a gear member for controlling closing of said first-mentioned valve, and a pawl and ratchet assembly adapted to permit periodic movement of said gear member.

11. The mechanism of claim 10 wherein said valves are spring-biased in a closing direction and wherein said second and third compartments are provided with air outlet means.
